(57) **CLAIM**

The ornamental design for an ultrasound applicator, as shown and described.

DESCRIPTION

FIG. 1 is a front perspective view of an ultrasound applicator of the present design;

FIG. 2 is a rear perspective view thereof;

FIG. 3 is a top plan view thereof;

FIG. 4 is a front elevation view thereof;

FIG. 5 is a right side elevation view thereof, the left side elevation view being a mirror image thereof;

FIG. 6 is a bottom plan view thereof;

FIG. 7 is a rear elevation view thereof;

FIG. 8 is a rear perspective view of the ultrasound applicator of FIGS. 1-7 with an environmental, disclaimed ultrasound coupling bandage shown in broken lines;

FIG. 9 is a rear perspective view of the ultrasound applicator of FIGS. 1-7 shown with an environmental, disclaimed coupling adapter attached to the bottom of the ultrasound applicator and with an environmental, disclaimed cord attached to the coupling adapter, where the coupling adapter and cord are shown as broken lines; and,

FIG. 10 is a rear perspective view of the ultrasound applicator of FIGS. 1-7 shown with an environmental, disclaimed ultrasound coupling bandage attached to the front of the ultrasound applicator, an environmental, disclaimed coupling adapter attached to the bottom of the ultrasound applicator, and with an environmental, disclaimed cord attached to the coupling adapter, where the ultrasound coupling bandage, coupling adapter, and cord are shown as broken lines.

The broken lines in the figures show environment and form no part of the claimed invention.
